United States Patent Office.

JAMES GONDOUIN, OF NEW YORK, N. Y., ASSIGNOR TO HIMSELF AND
FELIX AUMERLE, OF THE SAME PLACE.

Letters Patent No. 71,878, dated November 26, 1867.

IMPROVEMENT IN FUNNELS.

The Schedule referred to in these Letters Patent and making part of the same.

TO ALL WHOM IT MAY CONCERN:

Be it known that I, JAMES GONDOUIN, of the city and State of New York, have invented, made, and applied to use, a certain new and useful Improvement in Funnel; and I do hereby declare the following to be a full, clear, and exact description of the said invention, reference being had to the annexed drawing, making part of this specification, wherein—

Figure 1 is a vertical section of my improved funnel; and

Figure 2 is a plan of the same.

Similar marks of reference denote the same parts.

The object of this invention is to prevent the waste of liquids in the filling of bottles, barrels, and other vessels by the overflow of such liquids.

My said invention consists in a funnel provided with a valve, held up by a latch, that is relieved by the rising of a float, and allows the valve to fall and stop the further discharge of liquid from the funnel. By this device the funnel becomes self-closing, and the attendant can perform much more work than heretofore, because he does not have to examine and see when the vessel is full; he only has to supply the liquid into the funnel or series of funnels he may be using, and the rise of the liquid in the receiving-vessel causes the shutting off of further supply when a given point has been reached, the remainder of the liquid remaining in the funnel.

In the drawing, *a* represents the conical portion of the funnel, and *b* the nozzle. *c* is a valve-seat at the bottom of the tapering portion *a*, and *d* is a valve upon a hollow stem, *e*, that is guided in the bridges *f* and *i*. *g* is a float with a stem or light wire, *h*, extending up in the valve-stem *e*, and terminating as a ball or block, *n*. *l* is a latch upon a fulcrum, *k*, that has an inclined lower end, and *m* is a feather upon the stem *e*, to guide it in the bridge *f*, and also provided with a head below the bridge to prevent the valve, stem and latch *l* being raised above the point shown in fig. 1, where it will be seen that the ball *n* within the stem *e* prevents the latch *l* passing into said stem; hence that the valve and stem will be held up by the inclined end of said latch, but when the liquid running through the funnel rises in the vessel so as to lift the float *g*, the block *n* moving up allows the latch to turn into the stem *e*, and the valve *d* instantly closes, retaining the contents of the funnel, and preventing waste by overflow. The funnel is again caused to discharge its contents by simply lifting the stem *e*, and valve *d*, the weight of the float causing its ball *n* to press out the latch to the position of fig. 1.

What I claim, and desire to secure by Letters Patent, is—

The funnel *a*, and valve *d*, in combination with a float, *g*, latch *l*, and block *n*, substantially as and for the purposes set forth.

In witness whereof I have hereunto set my signature, this 11th day of October, 1867.

J. GONDOUIN.
